CURRENCY BANK

Philip K. Barker, New Canaan, Conn., assignor to Tom Thrift Enterprises, Incorporated, New Canaan, Conn., a corporation of Connecticut

Application February 9, 1953, Serial No. 23,490

Term of patent 14 years

(Cl. D34—11)

Fig. 1

Portions of the drawing figures are diagonally lined to indicate transparency.

I claim:

The ornamental design for a currency bank, as shown and described.
